United States Patent Office.

CHARLES H. YOUNG, OF RIVER POINT, RHODE ISLAND.

Letters Patent No. 81,453, dated August 25, 1868.

IMPROVEMENT IN LET-OFF MECHANISM FOR LOOMS.

The Schedule referred to in these Letters Patent and making part of the same.

TO ALL WHOM IT MAY CONCERN:

Be it known that I, CHARLES H. YOUNG, of River Point, in the county of Kent, and State of Rhode Island, have invented an Improved Let-Off Motion for Looms; and do hereby declare the following to be a full and correct description thereof, reference being had to the accompanying drawings, making part of this specification, and to the letters and numbers of reference marked thereon, similar letters and numbers being used in all the figures to denote the same part.

In these drawings—

Figure 1 is an elevation of the end of a loom, showing the "let-off" mechanism.

Figure 2 is a view of the escapement and wheel.

Figure 3 is a view of the same.

Figure 4 is a vertical section of the same, taken through in the direction of the red line in fig. 1.

The nature of this invention consists in making a let-off motion for a loom that shall not only allow the proper amount of warp to be drawn off of the yarn-beam, as required, but also, when an extra strain is put upon the web by the shuttles getting caught in the shed, to allow of the extra amount of warp to be drawn off by the action of the lathe, that may be necessary to prevent any damage to the web by the shuttle.

The construction is as follows:

A is the end frame of the loom.

B is the yarn-beam in bearings at the back of the frame.

C is a gear-wheel fast on the end of the short shaft S, on the other end of which is a small gear-wheel, which meshes into a larger wheel, z, on the yarn-beam. A small gear, t, is placed upon a stud just above the wheel C and meshes into it. The escapement-wheel D is fast to the small gear, and has projections, r r r, upon its face, which projections do not reach to the centre of wheel, but stop short, so as to leave a clear space in the middle.

F is the whip-roll, over which the warp passes from the yarn-beam to the harness. On the end of this whip-roll is an arm, P, which holds the escapement J, the ends of which are made with dogs or projections, o o, (see fig. 4,) which extend in towards the wheel D, so as to pass between the projections r r r, and is so arranged that one of the projections o will be in between those marked r r, when the other is outside of them, and vice versa.

V is a weight that keeps a proper strain upon the whip-roll to keep the web taut.

The operation is as follows:

As often as the warp becomes sufficiently taut from the filling, it causes a motion of the whip-roll by pressing upon the strip g. This motion vibrates the arm of the escapement, and allows a tooth of the wheel D to escape, and this, by means of the intermediate gear-wheels, lets a small portion of the yarn off of the beam. Thus it will be seen that the amount of yarn let off is governed by the pressure of the lathe (or lay) upon the filling, that is, when the process of weaving is going on, but if the shuttle gets stopped in the shed, and the lathe beats against it, the extra strain upon the warp will cause the whip-roll to move so far as to throw the arm of the escapement inside of the projections on wheel D, (see dotted lines in fig. 3,) and this leaves the wheel free to revolve, and allows the warp to be drawn freely from the yarn-beam, so as to prevent the shuttle caught in the web from doing any damage to it.

If it is necessary at any time to unroll or roll up the yarn on the beam, by moving the escapement-arm into the position shown by the dotted lines in fig. 3, the yarn-beam will be free to be moved by hand in either direction.

Having thus described my improved let-off motion, what I claim as my invention, and desire to secure by Letters Patent, is—

The combination of the wheel D with the escapement J, arranged so that the projections o o on the arms shall move clear of the projections r r on the wheel D, when any extra strain is thrown upon the warp, substantially as herein described and for the purpose set forth.

CHARLES H. YOUNG.
